UNITED STATES PATENT OFFICE.

WILLIAM F. WEIDENBAUM, OF CHICAGO, ILLINOIS, ASSIGNOR TO SCHRAM BROS. COMPANY, OF CHICAGO, ILLINOIS, A CORPORATION OF ILLINOIS.

CONVERTIBLE TABLE AND DESK.

1,163,291.

Specification of Letters Patent. Patented Dec. 7, 1915.

Application filed March 4, 1915. Serial No. 12,078.

To all whom it may concern:

Be it known that I, WILLIAM F. WEIDENBAUM, a citizen of the United States, residing at Chicago, in the county of Cook and State of Illinois, have invented a new and useful Improvement in Convertible Tables and Desks, of which the following is a specification.

My invention relates to an improvement in the class of convertible tables and desks in which the table-top is forwardly slideable to uncover a sunken case, such as a case of pigeon-holes, to permit the latter to be raised to extend above the table top at the rear side of the table for temporarily converting the latter into a desk.

The features to which my improvements are more particularly directed are the table-top, by adapting it, upon moving it forwardly, to uncover the case, to be moved backwardly partway; after raising the case, underneath the latter to form a solid supporting bed therefor; to the table-drawer, to cause it to be moved with the top in adjusting the latter to its different positions, whereby the drawer is rendered equally accessible in either of the table or desk positions of the top; to an automatically adjustable gate for covering the face of the pigeon-hole case in its sunken position to prevent the contents of the pigeon-holes from falling out, and for carrying the counterbalancing weight or weights for the case; and to means for frictionally controlling the raising and lowering of the case to tend to prevent slamming thereof into either position.

In the accompanying drawings, Figure 1 is a perspective view showing my article of furniture in its form of a desk; Fig. 2 is a section on line 2, Fig. 1; Fig. 3 is a section on line 3, Fig. 4; Fig. 4 is a view like that presented in Fig. 2, but showing the parts in the desk-forming position; Fig. 5 is a broken plan view of the article with the top removed to disclose details; and Fig. 6 is a section on line 6, Fig. 2.

The base portion of the article of furniture which is shown to include four corner-legs, may be of the design illustrated or of any other desired general design. The side-members 7 of the frame carry on their upper edges strips 8, which project outwardly beyond the faces of those members and are beveled along their outer edges to conform

to the beveled inner edges of guide-cleats 9 on the bottom of the table-top 10 at its lateral edges. The table-top is slideable back and forth on these strips and is confined on them against rising by this beveled junction 60 with the cleats. A drawer 11 is supported in guides 12, on the under side of the table-top, from which also extends a stop 13 to prevent pulling out the drawer, which is removable through an opening 14^a provided 65 in the front member 14 of the frame.

A pigeon-hole case 15 is supported in the back of the table-frame to be lowered into it below and raised out of it above the plane of the table-top. As means for thus adjustably supporting this case are shown guide-legs 16 as extensions of its rear corners to enter vertical guide recesses 17 formed in the inner faces of the rear table-legs when the case is in its lowered or housed position; 70 and each leg 16 has a link-connection 18 from its lower end with the inner end of a lever 19, fulcrumed at 20 in a bearing on the inner face of the adjacent side-member 7 of the frame, these levers terminating at 75 their opposite ends in feet 20^a. A board 21, forming a gate for the pigeon-hole case in its housed position, is seated on and fastened at its ends to the lever feet. This gate carries on its outer face counterbalancing 80 weights 22, one near each end, and on its ends pivotal concavely faced brake shoes 23 to bear frictionally against the curved edges of the guide-cheeks 24 rigidly secured in proper position opposite each other to 85 the inner faces of the side frame-members 7 and each terminating at its opposite ends in stops 25. Moreover, when the case 15 is raised into the desk-forming position, it may be sustained therein by the shoes bearing 95 downwardly against the guide-cheek edges adjacent the lower stops 25, unless the case be unduly heavy, as it would be rendered by overloading the pigeon-holes with contents, in which event the section of the sliding top which enters underneath the case 100 will solidly support it.

The article has been converted into the desk represented in Figs. 1 and 2 by drawing forwardly the table-top far enough to 105 clear the case 15 and permit it to be raised, the drawer moving with the table-top, and thereupon taking hold of the case of pigeon-holes and raising it slightly above the plane 110 of the table-top, which is then moved back- 115

wardly underneath the case as far as possible, when the case is pressed downwardly to rest on the table-top, whereby the latter affords a solid supporting bed for the pigeon-holes. In thus raising the case 15 it was counterbalanced throughout the movement by the weights 22, which furthermore served to press the shoes 23 against the curved guides 24, thereby tending to prevent slaming of the case into its raised position; and this movement of the pigeon-holes so turned the levers 19 on their fulerums as to lower the gate 21 away from its barrier position into that represented in Fig. 2. To convert the desk into a flat-top table, the top 10 is again moved forwardly until it clears the forward edge of the bottom of the case 15, which is then depressed to lower and house it in the frame, in attaining which position it is frictionally guided by the brake-shoes bearing under the stress of the weights against the curved edges of the cleats 24 in the same way as in raising it in the manner described; and in the lowering movement the accompanying turning of the levers on their fulerums brings the gate in front of the pigeon-holes to form a barrier against dropping out of their contents. As will be seen, the drawer always occupies the same position relatively to the table-top, so that with the latter in either of its two positions, the drawer is equally accessible.

I realize that considerable variation is possible in the details of construction thus specifically shown and described, and I do not intend by illustrating a single, specific or preferred embodiment of my invention to be limited thereto; my intention being in the following claims to claim protection upon all the novelty there may be in my invention as fully as the state of the art will permit.

What I claim as new and desire to secure by Letters Patent is:

1. In a convertible table and desk provided with a rear case supported to be raised and lowered for effecting the conversion, a top adjustable to cover the case in its lowered position and to extend underneath the case in its raised position.
2. In a convertible table and desk, the combination with a frame, of a case supported in the rear part of the frame, to be raised into the desk-forming position and

depressed into the frame for lowering it therein, and a table-top slidably supported on said frame to be moved forwardly for clearing said case and backwardly to cover said case when lowered, and extended underneath the case in its raised position.

3. In a convertible table and desk, the combination with a frame, of a pigeon-hole case supported in the frame to be raised into the desk-forming position and depressed into the frame for housing it therein, a gate connected with said case to be lowered by raising the latter and raised into barrier-position in front of the pigeon-holes by lowering said case, and a table-top adjustably supported on the frame.

4. In a convertible table and desk, the combination with a frame, of a pigeon-hole case supported in the frame to be raised into the desk-forming position and depressed into the frame for housing it therein, a gate connected with said case to be lowered by raising the latter and raised into barrier-position in front of the pigeon-holes by lowering said case, a counterbalancing weight on the gate, frictional guiding means on the frame and gate for guiding the gate in its movements, and a table-top adjustably supported on the frame.

5. In a convertible table and desk, the combination with a frame, of a pigeon-hole case, levers fulcrumed on the frame and having link-connections with said case, a weighted gate on said levers, pivotal brake-shoes on the gate, curved guides on the side-members of the frame frictionally engaged by said shoes, and a table-top adjustably supported on the frame.

6. In a convertible table and desk, the combination with a frame, of a pigeon-hole case having depending guide-legs, levers fulcrumed on the frame and having link-connections with said legs, a weighted gate on said levers, pivotal brake-shoes on the gate, cheeks on the opposite side-members of the frame, forming curved guides provided with stops, and pivotal brake-shoes on the gate engaging said guides.

WILLIAM F. WEIDENBAUM.
